DESIGN FOR A DISPLAY STAND

Lansing P. Shield, Ridgewood, N. J.

Application December 8, 1945, Serial No. 124,519

Term of patent 14 years

(Cl. D80—9)

To all whom it may concern:

Be it known that I, Lansing P. Shield, a citizen of the United States, residing at Ridgewood, in the county of Bergen, State of New Jersey, have invented a new, original, and ornamental Design for a Display Stand, of which the following is a specification, reference being made to the accompanying figures of the drawing, forming a part thereof.

Fig. 1 is a perspective of the display stand embodying my design, and

Fig. 2 is a side elevation of the stand.

I claim:

The ornamental design for a display stand, substantially as shown.

LANSING P. SHIELD.
